GAS FUEL MIXING DEVICE

Ferdinand G. Welke, San Francisco, Calif., assignor to Shell Development Company, San Francisco, Calif., a corporation of Delaware

Application May 21, 1935, Serial No. 22,539

1 Claim. (Cl. 48—180)

This invention relates to devices for the mixing of a gaseous fuel with air to form a combustible mixture and in particular relates to devices for the metering varying amounts of air and gas to the intake manifold of an internal combustion motor.

It has for some time been the practice in certain localities to operate internal combustion motors on gaseous fuel for example propane, butane, methane and various other gaseous hydrocarbon mixtures such as coal gas, oil gas etc.

Under conditions of fairly constant speed and load as for example where internal combustion motors are used for pumping or the generation of electricity the operation on gaseous fuel has been quite satisfactory. However where motorized units such as automobiles, buses and trucks have been operated on such gaseous fuels considerable trouble has been experienced due to the inability to obtain the desired power and acceleration under all driving conditions.

Such deficiencies in power and acceleration at certain load and speed conditions of the motor are commonly known as "flat spots".

It is an object of this invention to devise an apparatus which will eliminate flat spots in the operation of a motor on gaseous fuel. Another object of this invention is to devise a gas mixing device which will deliver the correct proportion of air and gas to the motor over the entire operation range. A further object of this invention is to provide a gas fuel mixing device which may be readily fitted to the carburetor air intake of an internal combustion motor fitted with a gasoline carburetor. The further objects of this invention will be apparent to those skilled in the art from the following detailed description of a specific embodiment of my invention throughout which reference is made to the accompanying drawings of which,

Fig. I is an end elevation of the gas mixing device partly in section.

Fig. II is a vertical section along line 2—2 of Fig. I.

Fig. III is a plan view of flapper valve.

Fig. IV is a side elevation of the flapper valve.

Fig. V is an elevation showing the device in position and connected for operation.

Fig. VI is a vertical section of gas regulator suitable for use with my device. Referring to Figures I and II the body of the device consists of a hollow casting (1) and a plate (2) the whole forming a box-like structure of approximate triangular shape. The lower face (3) of the device is adapted to fit the air intake (4) of the car-

buretor of an internal combustion motor. The plate (2) is provided with an air inlet port (5) and a gas inlet port (6) arranged with their centers on a common vertical line. The air inlet port is provided on its exterior side with a concentrically mounted collar (7) which together with the port (5) forms the air inlet. The gas inlet port (6) is provided on its exterior side with an adjusting flange (8). The flange (8) is attached to the plate by means of machine screws passing through openings in the flange. One of said openings is slot shaped so that the flange (8) may be moved laterally on the plate (2). Screw-threaded into a central opening in the flange (8) is a gas nozzle (9). The distance to which the gas nozzle is screwed into the flange is adjusted by means of an adjusting collar (10) and locking nut (11) the latter being screw-threaded onto the nozzle (9). Covering the air and gas ports (5) and (6) is a flapper or plate valve (12) hinged to the interior wall of the body above the gas port (6) by means of a hinge pin (13). The flapper valve, the details of which can be seen in more detail by referring to Figures III and IV, is of such size that it covers the gas port (6) and air port (5) when the valve is in vertical position as shown in Fig. II. A spring (14) is coiled around the hinge pin (13) and attached at one end to the middle of the plate on its inward side by a machine screw and nut (15). In assembled position as shown in Fig. II the other end of the spring (14) contacts the opposite interior wall of the body (1). The flapper (12) is perforated in its upper midsection at (16) as shown in Fig. III at a point above air port (5) and below gas port (6) and for a reason which will hereinafter appear.

A second spring (17) having its mid point attached to the middle of the flapper (12) by the means shown at (15) is so arranged that its free ends (17) press against the plate (2) when the flapper valve is closed, tending to force the flapper away from its closed position. The second spring (17) is not as strong as the spring (14) consequently the valve normally rests in closed position.

The object and function of this second spring will be explained later herein. The slanting face (18) of the body (1) has a port (19) so that the interior of the device can be placed in communication with the outside air. This port (19) is normally kept closed by means of an outwardly opening valve (20) held in closed position by a leaf spring (21), one end of said spring being attached to the center of the valve (20) and the other end being attached to the body, as will be seen in Figure II. As shown in Figure V the de-

vice above described is attached at its lower end (3) to the carburetor air intake (4) of an internal combustion motor (33) by a suitable connecting means (36). The gas nozzle is connected by suitable flexible hose (22) to the outlet side of a gas regulator (23) so adjusted that gas will pass to the device upon the creation of a vacuum in the hose (22). The gas regulator is of conventional type and is shown in section in Fig. VI. Referring to this figure, the gas inlet piece (24) is connected to a source of gas under pressure and is closed at its termination point within the regulator body by a valve (25). The valve (25) is connected to one end of an arm (26) pivoted to the body at point (27). The other end of the arm is connected to the middle of a diaphragm (28) closing the interior of the regulator from the outside air. An adjustable spring (29) pushes against the arm (26) at the point where it is connected to the diaphragm (28) gas leaves the regulator by outlet pipe (30). The operation is as follows: Upon the lowering of the pressure in the outlet pipe (30) the diaphragm (28) moves upwards, and through the arm (26) causes the valve (25) to open allowing gas to enter the regulator. Upon the pressure in the regulator being raised, the diaphragm moves downward and shuts off the incoming gas supply. The regulator works automatically to maintain a fairly constant subatmospheric pressure in the hose (22) notwithstanding the varying amounts of gas flowing through. The amount of vacuum required to cause the flow of gas can be regulated.

I have found in practice that if the regulator is set to allow gas to flow through the hose (22) with a subatmospheric pressure of two inches of water below atmospheric, satisfactory operation is obtained. It should however, be borne in mind that the setting of the regulator for the best performance will depend upon many factors among which may be mentioned the distance between the regulator and gas mixer, the tension of spring (14) the type of manifolding on the motor etc., so that the adjustment of the regulator is preferably made for each individual installation by the engineer installing the same. When using the gas-air mixture the gasoline supply to the carburetor is shut off. The cross sectional areas of the gas nozzle (9) and the air port (5) as well as the distances of the gas nozzle and the air port from the hinge pin are so proportioned that the correct gas-air mixture is supplied to the motor. For example, when using propane with my device fitted to the air intake of a down draft carburetor of a particular motor I have found that with a diameter of the gas nozzle of .316", diameter of air port 1.5", distance of center of gas nozzle from the hinge pin .5", distance of center of air port to hinge pin, 2.75", a correct fuel-air ratio was maintained. The gas nozzle (9) can by means of the flange (8) be moved slightly towards or away from the hinge pin (13) by loosening the machine screw passing through the slotted opening in the flange (8). By this means the ratio of gas to air may be adjusted. By moving the gas nozzle laterally towards the

hinge pin (13) the proportion of gas in the mixture is reduced, by moving the nozzle laterally away from the hinge pin (13) the proportion of gas in the mixture is increased. The proportion of gas to air in the idling mixture is adjusted by screwing the gas nozzle either inward towards the flapper or outward away from the flapper by means of adjusting collar (10). The operation of the device is as follows: Upon the opening of the throttle valve (31) of the carburetor (35) and the turning over of the motor (33) by means of the electric starter or otherwise, a partial vacuum is produced in the interior of the device sufficient to cause the flapper (12) to raise from contact with the plate (2) so that air from the atmosphere and gas from the pressure side of the gas regulator are drawn into the motor as with a gasoline-air mixture.

Once the motor has started it will continue to run on the gas-air mixture, the amount of mixture passing to the motor being controlled by the throttle valve (31). The object of spring (17) is to prevent fluttering of the flapper valve at certain motor speeds. It is my theory that the spring sets up a counter vibration to the vibration of spring (14). It should be understood that I do not intend to limit myself to this theory. In practice I have found that the spring (17) is effective in preventing vibration or fluttering of the flapper valve when other attempts to prevent this were unsuccessful.

The provision of the opening (16) in the flapper valve (12) between the two ports (5) and (6) is for the purpose of permitting a more ready entry of gas from port (6) into the body of the device and to help maintain the correct gas-air ratio. The provision of the relief valve (20) is to provide a relief for the gases in the event of "backfire" of the motor for it will be apparent from the drawing that the gases would be unable to leave by way of the air inlet as is possible with the usual gasoline carburetor.

The particular device shown is designed for attachment to the air intake of an existing gasoline carburetor so that by turning off the gasoline feed and turning on the gas feed, the motor may be run on gas-air mixture or by turning on the gasoline feed and turning off the gas feed the motor may be operated on gasoline-air mixture. In installations where it is only desired to run on a gas-air mixture the device of my invention can be provided with a throttle valve (32) in its outlet toward the motor as shown in dotted lines in Fig. II. The unit in this case is attached directly to the induction manifold of the motor (33) without the intermediary of a carburetor.

I claim as my invention:

In a gas fuel mixing device for an internal combustion motor, the combination of an air inlet port, a gas inlet port, a flapper valve covering said ports, a first spring holding said flapper valve in contact with said ports, a second spring tending to hold said flapper valve away from said ports whereby periodic vibration of said flapper valve is prevented.

FERDINAND G. WELKE.
